UNITED STATES PATENT OFFICE.

CHARLES E. HARTIAN, OF LYNN, MASSACHUSETTS, ASSIGNOR TO THE GENERAL ELECTRIC COMPANY, OF NEW YORK.

DESIGN FOR AN ARC-LAMP.

SPECIFICATION forming part of Design No. 26,471, dated December 29, 1896.

Application filed November 27, 1896. Serial No. 613,695. Term of patent 14 years.

To all whom it may concern:

Be it known that I, CHARLES E. HARTIAN, a citizen of the United States, residing at Lynn, in the county of Essex, State of Massachusetts, have invented a new and original Design for Electric-Arc Lamps, of which the following is a specification.

The accompanying drawing shows an electric-arc lamp illustrating the invention.

10 The leading feature of the design is an enlarged top portion connected by a narrow neck with the main body of the lamp.

15 A indicates the main body of the lamp, of the usual cylindrical form, having the ribbed spreading flanged portion B at its lower end, from which depends the globe C of the lamp.

20 D indicates the top portion of the lamp, which is shown as cylindrical and enlarged and connected by a narrow neck E with the main cylindrical body portion A. The narrow neck E, as here shown, is of a mortar-shape form; that is, having a circular top and bottom F and a curved connecting portion G, forming the waist of the neck. This 25 neck portion E, while shown as short in length,

may be of any length desired. The enlarged portion D and the main body portion A may be provided with ornamental bands H, a single ornamental band H encircling the top portion and a pair of ornamental bands H 30 encircling the main body portion A, and, if desired, a ribbed bead-like portion or enlargement I may encircle the main body portion A centrally between the ends thereof.

The design, however, is not limited to the 35 particular ornamentation and configuration set forth, the essential feature thereof being an enlarged top portion and a narrow curved neck connecting the top portion with the main body portion of the lamp. 40

What I claim is—

The design for an electric-arc lamp, as herein shown and described.

In witness whereof I have hereunto set my hand this 10th day of November, 1896.

CHARLES E. HARTIAN.
